UNITED STATES PATENT OFFICE.

RICHARD H. UHRBROCK, OF TOWSON, MARYLAND.

WIRE-CLAMP.

1,103,711.

Specification of Letters Patent. Patented July 14, 1914.

Application filed April 6, 1914. Serial No. 829,984.

To all whom it may concern:

Be it known that I, RICHARD H. UHRBROCK, a citizen of the United States, residing at Towson, in the county of Baltimore and State of Maryland, have invented new and useful Improvements in Wire-Clamps, of which the following is a specification.

This invention relates to wire clamps such as are used for holding together the loose ends of wires while being spliced together or for other purposes.

One object of the invention is to provide a simple and efficient device whereby the loose ends of wires of a known or predetermined gage may be securely held together while being operated on.

A further object of the invention is to produce a simple and effective device of the class described comprising two jaw members having handles whereby they may be manipulated, means being provided for adjustment of the connecting means of the jaw members, whereby said jaw members will be adapted to grip and hold securely wires of predetermined gage when the handle members of the jaws are in alining position.

A further object of the invention is to produce an implement of the character described in which one of the jaw members may be provided with a detachable cutting or scoring member for the purpose of scoring or nicking one of the wires held by the implement to enable it to be readily severed when desired.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifi-

cations within the scope of the claims may be resorted to when desired.

In the drawing, Figure 1 is a top plan view of an implement constructed in accordance with the invention, a portion of the upper jaw member having been broken away. Fig. 2 is a bottom plan view. Fig. 3 is a longitudinal sectional view taken on the line 3-3 in Fig. 1. Fig. 4 is a sectional detail view taken on the line 4-4 in Fig. 1. Fig. 5 is a bottom plan view illustrating a modification.

Corresponding parts in the several figures are denoted by like characters of reference.

The "upper" and "lower" jaw members, so designated for convenience only, it being obvious that the relative position of said jaw members depends altogether on the position in which the tool is held, consist of disks 15, 16 having radially extending handles designated, respectively, by 17 and 18. The disks or jaws, which are preferably approximately circular in shape, are provided with central apertures 19, 20, for the passage of a connecting bolt 21 having a nut 22 inset in the external face of the upper jaw 15. The bolt 20 has a non-circular head 23 which is seated in a recess 24 in the lower member 16.

The head 23, as seen in Fig. 2 of the drawing, may be of regular polygonal shape, the recess or socket 24 being correspondingly shaped so that by unscrewing the member 15 having the inset nut 22, the head 23 may be partly turned about the axis of the bolt and then reseated in the socket or recess 24. The inner or working face of the lower jaw member 16 is roughened so it will take a firm hold on a wire or other substance inserted between the face of the jaws when said jaws are moved toward each other. The inner face of the lower jaw member 16 is also pro-

vided with a transverse groove or recess 25 wherein may be seated a cutting member 26 for the purpose of notching or scoring the end of a wire which may be placed across said cutting member, when it shall be desired to do so, in order that the end

of the wire may be subsequently broken off or detached easily and without the use of additional tools.

The handle of the jaw member 16 is provided with a notch or slot 27 in which a portion of a wire may be inserted for the purpose of holding the lower jaw member securely with respect to such wire.

Let it be assumed that in a certain position of the parts the handles 17, 18 of the jaw members 15, 16 extend in alinement with each other, as seen in Fig. 1. It follows that by rotating the bolt in the proper direction about its axis, the jaw members 15 will gradually be moved apart from each other. Means being provided consisting of the polygonal head 23 engaging the socket 24 for retaining the bolt in various positions, it follows that in various predetermined positions of the bolt head, the opposed faces of the jaws will be variously spaced apart, and these various positions, the number of which will correspond with the number of faces and angles of the bolt head, are calculated to vary according to the gage of various wires, so that, for example, in one position of the bolt head a wire of No. 9 gage will be clamped and held tightly between the faces of the jaws 25 when the handles 17, 18 are in alinement; in the next position a wire of a different gage, here indicated as No. 10 will be so held and so on. In view of the fact that in some wire gages the intervals of the gage 30 are not uniform, but irregular, the indicia 35 6 to 11, inclusive, seen in Fig. 2 of the drawing, are to be regarded as merely conventional and illustrative, the said indicia being shown as being equally spaced apart. 40 To indicate the proper position of the bolt head with respect to the wires of various gage, the said bolt head may be provided with an indicator, such as an arrow 28, and the external face of the jaw may be stamped 45 adjacent to the angles of the recess 24 with numerals, as clearly seen in Fig. 2, to indicate the proper position of the bolt head when the tool is to be used to clamp wires of certain predetermined gage. This will 50 enable the connecting bolt to be correctly adjusted whenever the tool is to be used, but such adjustment will not be frequently required, inasmuch as the tool will rarely, if ever, be used on any one job for the purpose 55 of clamping wires of more than one predetermined gage.

Under the modified construction illustrated in Fig. 5, the bolt head, here designated by 23', is provided with a laterally 60 extending projection or key 29 which may be placed in engagement with any one of a plurality of notches 30 extending from

the recess or socket which is here designated by 24'. It will be readily observed that any construction that permits of axial adjustment of the bolt against rotation at predetermined adjustments will fall within the scope of the appended claims.

It will be seen that in practical operation, when this tool is used for the purpose of operating on wires of any predetermined gage, assuming the connecting bolt to have been previously adjusted or set to the proper position, the wires will be held and securely clamped between the faces of the jaw members when the handle members 17, 18 are in alinement with each other, this position of the handles serving to indicate when the wires are firmly clamped. At such time the tool may be very conveniently handled and manipulated, as will be readily understood.

Having thus described the invention, what is claimed as new, is:—

1. A wire clamp comprising opposed jaw members, each having a radial handle member, and a connecting bolt, said bolt having a head inset in one jaw member and a nut inset in the other jaw member.

2. A wire clamp comprising opposed jaw members, each having a radial handle member, and a connecting bolt, said bolt having a head inset in one jaw member and a nut inset in the other jaw member; the bolt head being of non-circular shape and the jaw member in which it is inset being constructed to retain the bolt head securely at various predetermined axial adjustments.

3. A wire clamping device comprising jaw members each having a radial handle, a bolt extending through the jaw members and having a non-circular head inset in one jaw member and capable of predetermined axial adjustments, a nut inset in the other jaw member, and indicia on the bolt head and on the face of the jaw member in which it is inset to indicate predetermined adjustments.

4. A wire clamp comprising clamping jaws each having a radial handle and a threaded connecting member axially adjustable with respect to one jaw member, the other jaw member being provided with an inset nut engaging the threaded connecting member.

5. A wire clamp comprising jaw members each having a radial handle, and a threaded connecting member axially adjustable with respect to one jaw member and in threaded engagement with respect to the other jaw member.

6. A wire clamp comprising jaw members each having a radial handle, and a threaded connecting member axially adjustable with

respect to one jaw member and in threaded engagement with respect to the other jaw member; one of the jaw members having a roughened face, and the handle of said jaw member having a wire receiving notch.

7. A wire clamp comprising clamping jaws having a radial handle and a threaded connecting member axially adjustable with respect to one jaw member, said last mentioned jaw member having a groove and an

indenting member seated therein; the threaded connecting member being in threaded engagement with respect to the other jaw member.

In testimony whereof I affix my signature 15
in presence of two witnesses.

RICHARD H. UHRBROCK.
